(57) **CLAIM**

The ornamental design for a headlight case for a motorcycle, as shown and described.

DESCRIPTION

FIG. 1 is a front, right perspective view of a headlight case for a motorcycle showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom view thereof; and,

FIG. 7 is a front, left perspective view thereof.

The broken lines in the drawings illustrate portions of the headlight case for a motorcycle that form no part of the claimed design.
